US00D540257S

(12) **United States Design Patent** (10) **Patent No.:** **US D540,257 S**
Ivanova et al. (45) **Date of Patent:** **** Apr. 10, 2007**

(54) **ELECTRICAL ADAPTER**

(76) Inventors: **Irina Ivanova**, 164 E. 33rd St. Apt. 9, New York, NY (US) 10016; **Botir T. Sagdullaev**, 164 E. 33rd St. Apt. 9, New York, NY (US) 10016

(**) Term: **14 Years**

(21) Appl. No.: **29/242,439**

(22) Filed: **Nov. 11, 2005**

(51) **LOC (8) Cl.** **13-03**

(52) **U.S. Cl.** **D13/137.2**

(58) **Field of Classification Search** .. D13/137.1-137.4, D13/138.1, 138.2, 139.1, 139.6-139.8, 133, D13/154, 156; 439/171-172, 140, 160, 164, 439/135-138, 446, 131, 606, 105-106, 11, 439/13, 31, 650-655, 628, 476.1, 478, 480, 439/483-484, 696, 692, 645-646; 174/53-58; 337/197-187

(57) **CLAIM**

The ornamental design for an electrical adapter, as shown and described.

DESCRIPTION

FIG. 1 is a left, front, and top perspective view of our new design for an electrical adapter;

FIG. 2 is a left side elevation view of the electrical adapter shown in FIG. 1;

FIG. 3 is a front side elevation view of the electrical adapter shown in FIG. 1;

FIG. 4 is a top plan view of the electrical adapter shown in FIG. 1;

FIG. 5 is a right side elevation view of the electrical adapter shown in FIG. 1;

FIG. 6 is a rear elevation view of the electrical adapter shown in FIG. 1; and,

FIG. 7 is a bottom plan view of the electrical adapter shown in FIG. 1.

The broken line showing is for illustrative purposes only and forms no part of the claimed design.
